(57) **CLAIM**

The ornamental design for a folded wing rocket aircraft, as shown and described.

DESCRIPTION

FIG. 1 is a front elevational view of a folded wing rocket aircraft showing my new design.

FIG. 2 is a back elevational view.

FIG. 3 is a top plan view.

FIG. 4 is a bottom view.

FIG. 5 is a right side elevational view.

FIG. 6 is a left side elevational view; and,

FIG. 7 is a perspective view.
